UNITED STATES PATENT OFFICE.

ARCHIE E. PARNALL, OF CHICAGO, ILLINOIS, ASSIGNOR TO FRANK W. WILLIAMS,
OF CHICAGO, ILLINOIS.

AUTOMATIC STOP FOR TALKING-MACHINES.

1,345,398.

Specification of Letters Patent.

Patented July 6, 1920.

Application filed August 21, 1917, Serial No. 187,392. Renewed May 22, 1920. Serial No. 383,544.

To all whom it may concern:

Be it known that I, ARCHIE E. PARNALL, a citizen of the United States, and a resident of the city of Chicago, in the county of Cook and State of Illinois, have invented certain new and useful Improvements in Automatic Stops for Talking Machines; and I do hereby declare that the following is a full, clear, and exact description of the same, 10 reference being had to the accompanying drawings, and to the numerals of reference marked thereon, which form a part of this specification.

This invention pertains to an automatically operated stop for talking machines and similar devices, in which a spring controlled brake mechanism is adapted to be held in an adjusted position releasably engaging a spring controlled lever which is 15 adapted to be actuated by the sound arm of a reproducer mechanism after the playing of a record to release the brake mechanism to permit the same to automatically engage the record carrying disk to bring the same to 20 a stop.

It is an object of this invention to provide a device for phonographs serving to automatically bring the operating mechanisms to a stop after the playing of a record.

Another object of this invention is the construction of a spring controlled mechanism adapted to be automatically actuated by the sounding arm of a phonograph to bring a record carrying disk to a standstill 30 after the playing of a record.

It is furthermore an object of this invention to provide a pivotally mounted arm adapted to be actuated by the reproducer mechanism of a talking machine to release 40 spring controlled levers to permit a brake on one of said levers to frictionally engage the record carrying disk to bring the same to a stop at any desired point in the playing of a record.

An important object of the invention is the construction of a talking machine stop wherein a brake is adapted to be manually set in a position from which the same is automatically released from engagement 50 with a spring controlled locking lever by a controlling arm which is adapted to be contacted by the pivoted sounding arm of the reproducer mechanism of the talking machine to cause the brake to frictionally engage the record carrying disk of the talk-

ing machine to bring the same to a stop at the desired set position.

Other and further important objects of the invention will be apparent from the disclosures in the specification and drawings. 60

The invention (in a preferred form) is illustrated in the drawings and hereinafter more fully described.

On the drawings:

Figure 1 is a top plan view of a talking 65 machine equipped with a stop mechanism embodying the principles of this invention.

Fig. 2 is an enlarged fragmentary view similar to that shown in Fig. 1, with the operation of the device indicated by dotted 70 lines.

Fig. 3 is an enlarged sectional view taken on line 3—3, of Fig. 2, with parts omitted.

Fig. 4 is an enlarged top plan view of the device. 75

Fig. 5 is an elevational view of one side thereof.

Fig. 6 is a view taken on line 6—6, of Fig. 4, with parts broken away.

Fig. 7, is a section taken on line 7—7, of 80 Fig. 4, with parts shown in elevation and with parts broken away.

As shown on the drawings:

The reference numeral 1, indicates the top board of a talking machine casing upon 85 which is rotatably mounted a record carrying disk, 2, having a record 3, disposed thereon in a customary manner to rotate therewith. Mounted near one side of the top board 1, and extending upwardly therefrom 90 is a stub pipe or tube 4, having pivotally mounted thereon an elbow 5, in the end of which is secured a reproducer sounding arm 6. Secured in the outer end of the sounding arm 6, is a sound box 7, of any desired type 95 adapted to carrying a record playing needle, for playing the record when the same is rotated with the record carrying disk.

Securely mounted by means of screws 8, or other suitable means upon the top board 100 1, to the outside of the disk 2, and to one side of the reproducer supporting pipe 4, is a base plate 9, having pivotally mounted near one side thereof by means of a pivot pin 10, a stop arm or lever 11, the outer end 105 of which is curved outwardly and has secured thereon a knurled head or handle 12.

Integrally formed or rigidly secured on the inner edge of the stop arm 11, near the curved end thereof is an upwardly directed 110

projection or finger 13, around which is disposed a brake shoe 14, made of rubber or any other suitable material. Integrally formed on the pivoted end of the stop arm 5 11, is a longitudinally directed flat extension arm or lever 15, which is a continuation of the inner margin of the stop arm 11, and lies in the plane of said stop arm which is also preferably flat. The outer end of the 10 extension arm 15, is bent upwardly at right angles to form a hook or latch 16. To limit the outward swing of the stop arm 11, about the pivot pin 10, an abutment 17, is secured upon the base plate 9, in a position to be 15 contacted by the inner edge of the extension arm 15. Mounted upon the base plate 9, to the rear of the stop arm 11, is a leaf spring 18, which has the middle portion thereof engaged around a retaining screw 19. One 20 arm of said spring 18, is engaged behind a nub or projection 20, formed on the inner edge of the base plate 9, while the other arm of said spring engages a nub or projection 21, secured on the inner edge of the stop arm 25 11, thus affording a means for normally pulling the stop arm inwardly to permit the brake shoe 14, to frictionally engage the periphery of the record carrying disk 2, as shown in dotted lines in Fig. 2. Of course 30 it will be understood that any suitable type of spring or other means may be used to exert a pull on the outer end of the stop arm to normally permit the brake shoe to contact the disk 2.

35 Pivottally mounted at one corner of the base plate 9, adjacent the reproducer stub pipe 4, is a vertical shaft 22, to which is rigidly secured by means of a clamp or bracket 23, an angled arm or lever 24, one angled 40 end of which is secured in the clamp bracket 23, while the other end is slightly curved and bent upwardly adjacent and to one side of the sounding arm 6, to permit said sounding arm to contact the same after the playing 45 of a record to actuate the brake mechanism as hereinafter described. Rigidly engaged on the lower end of the vertical shaft 22, and above the base plate 9, is a finger or lever 25, offset at a point between the ends thereof to 50 permit the other or free end of the finger to laterally cross over the extension arm 15, of the stop arm, to permit the latch 16, of said extension arm to lockingly seat in a notch 26, formed in the outer edge of the finger 25, 55 when the stop arm 11, is in its outer position, as shown in Fig. 4, to hold the actuating arm 24, in an adjusted set position to be contacted by the sounding arm 6, after the playing of a record. To hold the finger 25, 60 engaged against the latch 16, to prevent a swinging movement of the actuating arm 24, a spring 27, is looped around the vertical shaft 22, and has one end thereof secured to the edge of the base plate 9, and the other 65 end thereof engaged around the inner edge

of the finger 25, to force the free end of said finger against the latch 16.

The operation is as follows:

When it is desired to set the stop mechanism of a talking machine so that the stop 70 will act automatically after the playing of a record or at any point on the record, the playing needle secured in the reproducer stylus mounted on the end of the sounding arm 6, is first set with the needle in the last 75 or innermost groove in the record 3, or at any other desired point on the record at which it is desired to bring the record carrying disk 2, to a standstill. The actuating lever 24, is then manually moved into a position 80 wherein the curved angled free end of said lever abuts or contacts one side of the sounding arm 6. In this adjusted or set position of the stop mechanism the latch 16, of the stop arm 11, seats in the notch 26, of 85 the finger 25, thereby holding the stop arm in its outermost position as shown in full lines in Fig. 4, against the action of the spring 18, which is stressed. The spring 27, secured to the base plate 9, and to the finger 90 25, tends to hold the finger 25, forced against the latch 16, thereby locking the stop mechanism in a set or adjusted position. The reproducer arm is now swung outwardly away from the actuating lever 24, 95 into a position wherein the needle is adapted to engage in the outer most groove of the record to permit playing of the record from the beginning. The talking machine starter is now operated to start the machine thus 100 causing rotation of the record carrying disk 2, and the record 3, to permit the needle to play said record, whereby the reproducer arm moves inwardly with respect to the record until the sounding arm 6, contacts the 105 angled upwardly projecting free end of the stop actuating lever 24, which is thereby swung with the shaft 22, against the stress of the controlling spring 27, thus simultaneously swinging the finger 25, away from 110 the latch 16. The action of the stressed spring 18, is thus exerted to pull the stop arm 11, inwardly thereby forcing the brake shoe 14, against the periphery of the record carrying disk 2. The friction between said 115 brake shoe and disk brings the disk to a stop within a very short time at the desired set position of the stop actuating lever 24.

If at any time it is desired to bring the record carrying disk and record to a stop 120 at a point other than at the end of the record, the clamp 23, which supports the lever 24, on the shaft 22, may be turned on the shaft 22, into a position in which the latch 16, engages in the notch 26, of the finger 25, 125 and in which the free end of the actuating lever 24, is positioned at the desired point to be contacted by the sounding arm 6, of the reproducer mechanism.

It will of course be understood that the 130

springs 18 and 27, may be of any desired type and that numerous other details of construction may be varied through a wide range without departing from the principles of this invention, and I therefore do not purpose limiting the patent granted otherwise than necessitated by the prior art.

5 I claim as my invention:

A talking machine mechanism embracing 10 a base plate, an arm pivoted thereon, a latch and a brake shoe on said arm on opposite sides of the pivot point of said arm, a spring on said base plate connected with said arm for normally holding the same in braking 15 position, a shaft pivoted on said base plate, a clamping bracket engaged on said shaft, an actuating lever secured therein, a mem-

ber secured to said shaft, and a spring engaging around said shaft and attached to said base plate and to said member, said 20 arm being adapted to be pulled outwardly against the action of said arm spring to permit said latch to lockingly engage said member to hold said lever in a set position whereby said brake shoe is held in a re- 25 tracted position.

In testimony whereof I have hereunto subscribed my name in the presence of two subscribing witnesses.

ARCHIE E. PARNALL.
